United States Patent

Des. 239,939
Patented May 18, 1976

239,939

AIR INDUCTOR

David Anthony Whitbread, Luton, England, assignor to
F. Brauer Limited, Hertfordshire, England

Filed May 20, 1974, Ser. No. 471,201

Term of patent 14 years

Int. Cl. D23—04

U.S. Cl. D23—151

FIG.1.

FIG.2.

FIG.3.

FIG.4.

FIG.5.

FIG.6.

FIG. 1 is a side view of an air inductor embodying my new design;

FIG. 2 is a front view thereof;

FIG. 3 is a top plan view thereof;

FIG. 4 is a bottom plan view thereof;

FIG. 5 is a view taken from the side opposite that shown in FIG. 1; and

FIG. 6 is a rear view thereof.

I claim:

The ornamental design for an air inductor, as shown.
